UNITED STATES PATENT OFFICE.

OSCAR FINLEY TALLMAN, WILLIAM PAUL KIMBROUGH, AND LOUIS JAMES REYNOLDS,
OF SHERMAN, TEXAS.

TIMER FOR IGNITION SYSTEMS.

Application filed August 23, 1924. Serial No. 733,825.

To all whom it may concern:

Be it known that we, OSCAR FINLEY TALLMAN, WILLIAM PAUL KIMBROUGH, and LOUIS JAMES REYNOLDS, citizens of the United States, residing at Sherman, in the county of Grayson and State of Texas, have invented new and useful Improvements in Timers for Ignition Systems, of which the following is a specification.

10 This invention relates to timers for ignition systems of internal combustion engines, and particularly to timers of that type embodying a rotary member carrying a spring-pressed brush adapted for engagement with 15 spaced contacts carried by a ring of insulated material mounted within the timer casing or shell.

One object of our invention is to provide 20 a timer having a novel construction of pressure spring for the brush, which spring is of considerable length and devoid of angles or interlocking connections in its movable parts liable to cause rapid fracture from crystallization or other causes, and which 25 spring has a self-locking connection with the rotor collar, thereby dispensing with the use of auxiliary fasteners, the construction of the spring further ensuring its free movements at all times.

30 A further object of the invention is to provide a novel and simple construction of rotor for supporting and guiding the brush and spring, and which serves to positively guide the brush in its movements and hold 35 the spring from displacement, and which will effectually prevent the brush or spring from becoming clogged with grease to any such extent as to interfere with their movements.

40 A still further object of the invention is to provide a construction of spring which will permit of the use of a comparatively long brush block of copper, ensuring better electrical engagement with the fixed contacts, avoiding the necessity of using a steel brush or an excessive amount of lubricant, liable to cause pitting and carbonization of the parts and imperfect engagement between the brush and stationary contacts.

50 With these and other objects in view, the invention consists of the features of construction, combination and arrangement of parts, hereinafter fully described and claimed, reference being had to the accompanying drawing, in which:

Figure 1 is a side elevation of our improved timer looking toward the outer side thereof and with the cap or cover removed.

Figure 2 is a central vertical section taken through the device on a line at right angles to its axis.

Figure 3 is a central section through the device taken parallel with its axis on the line 3—3 of Figure 1.

Figure 4 is a detail section on the line 4—4 of Figure 3.

Referring now more particularly to the drawing, 1 designates the end plate of the timing gear box of a timer of the character described, 2 the rotary timer shaft, 3 the timer casing or shell detachably connected with the plate 1, 4 a removable cap or cover normally closing the open side of the shell, and 5 a spring or like fastener for holding the cap 4 in position, the same being secured to a post 6 projecting from the head 1. The shell 3 is provided as usual with an internal lining or ring 7 of insulating material in which are embedded the spaced stationary contacts 8 of the ignition mechanism.

75 A rotor 9 of novel form is provided in accordance with our invention to carry the timer brush 10. This rotor 9 is formed of a single casting and comprises a hub or sleeve 11 carrying at its inner side a circular flange 12 giving a proper bearing and balancing action in the rotation of said rotor. A second flange or wall 13 is arranged 80 outside this flange 12 in spaced relation thereto and to the outer end of the sleeve 11 and is connected with the flange 12 by spaced transverse walls 14, the flange 13 and walls 14 forming with a component part of the flange 12 a radial guide chamber or 85 guideway 15 to receive the brush 10 and hold it from displacement.

90 The brush 10 comprises an oblong rectangular solid block, of like form at each end, whereby it may be reversed, end for end, if desired in the event that one end should become improperly worn and it is desired to present a new surface for action. This block has its sides formed to slide between the flanges 14, its inner edge sliding 100 in engagement with a groove 16 in the flange 12 and its outer edge sliding in contact with the flange or wall 13, whereby an accurate guide motion of the block is ensured. The walls 14 are of comparatively short 105 110

radial depth and positioned adjacent to the outer peripheries of the flanges 12 and 13, thus providing a transverse opening 17 extending completely through the guideway 5 between the walls 14 and the sleeve 11.

A pressure spring 18 is provided for forcing the brush 10 outwardly into contact with the surface of the insulating ring 7 and the stationary contacts 8. This spring is of 10 novel form and made of flat spring metal, the inner portion of the spring being bent to provide a circular coil 19 surrounding the sleeve 11, and the outer portion of the coil being shaped to produce an incomplete 15 spiral coil 20. The coil 19 closely embraces the sleeve 11 and the inner end of the spring forming one terminal of this coil is provided with an indent tongue 21 to engage a groove or recess 22 in the sleeve, whereby 20 through the contractile energy of the coil 20 and locking engagement of the tongue 21 with the groove 22, the spring is fixed to the sleeve 11 in a secure manner without the use of auxiliary fastenings. The opposite end 25 23 of the spring 18, forming the terminal of the coil 20, extends through the slot 17 and bears against the inner end of the brush 10, the coil 20 thus acting as a pressure coil, the end 23 of which is movable in said slot, 30 for pressing the brush outwardly into contact with the surface of the ring 7 and the contacts 8 for proper operation of the rotor for a timing action in the working of the device.

The operation of the device will be readily understood from the foregoing description, taken in connection with the drawing, by those versed in the art, and it will be seen that a timer brush construction is provided 40 consisting of only three simple and rugged elements, to wit, the rotor with integral parts, the brush block and a flat coiled spring acting on the block. Due to the construction of this rotor and form of the spring employed, a spring having an acting portion 45 movable through a wide range of surface motion is produced and means provided whereby the working portion of the spring is rendered devoid of angles or interlocking 50 connections liable to cause rapid crystallization, breakage or impairment of the working action of the spring. The described construction of the spring further provides for its application to the rotor without the use 55 of auxiliary fastenings, and owing to the form of the working portion 20 of the spring, and its wide range of motion, it is not liable to be clogged by grease, so that a proper working action of the brush is at 60 all times ensured. This spring also enables a brush formed of a solid block of copper to be used, and which is of considerable wearing length, ensuring long life and better elec-

trical conductivity and, as the wearing action of such metal on the insulating ring 7 65 and contacts 8 is much less than that of steel or other hard metal, the necessity of frequently replacing the timer shell or casing is avoided. The use of a copper brush also allows the contact surfaces to keep clean and 70 dry, as the necessity for oil or other lubricant is avoided or reduced to the very minimum, avoiding pitting, crystallization and other objections causing imperfect firing incident to the use of oil or grease for lubricating purposes. Therefore, as the contact surfaces will always keep dry and clean, the hotter spark will be furnished, making the car start easier and run better and smoother. 75

Another advantage is that when it becomes necessary to renew the contact brush all that is required is to remove the timer case, lift out the contact brush, insert a new one, and replace the timer case, it not being necessary to remove the brush holder or 80 rotor, whereby considerable time and labor is saved over timers of ordinary construction. 85

Having thus fully described our invention, we claim:—

In a timer, a rotary shaft, a disk fixed to 90 the shaft and having a central sleeve projecting laterally from its outer face and embracing the shaft, a radial guideway carried by the sleeve and shaft, said guideway including an inner wall formed by a radially 95 recessed portion of the body of the disk, an outer wall extending radially from the disk parallel with said inner wall, and opposite transverse walls connecting said inner and outer walls outwardly beyond the transverse center of the guideway, said guideway being open at its sides between the inner 100 edges of said transverse walls and the periphery of the sleeve, the said sleeve being provided with a notch in a side thereof at right angles to the guideway, a brush movable in said guideway, and a flat metal spring having a substantially circular inner portion embracing the sleeve and a spiral outer portion lying beyond the sleeve, one 105 end of said spring constituting a terminal of said circular portion extending into and having an interlocking engagement with said notch, and the other end of said spring constituting a free terminal of said spiral portion, said free end terminal being arranged 110 to bear upon the inner end of the brush and extending across the guideway and through the open sides thereof and freely movable in two directions, both longitudinally and transversely of said guideway. 115 120

In testimony whereof we affix our signatures.
